STRINGED MUSICAL INSTRUMENT

John W. McBride, Burbank, Calif.

Application May 29, 1943, Serial No. 489,040

10 Claims. (Cl. 84—315)

1

This invention relates to a musical instrument; and, more particularly, to an instrument utilizing tensioned strings.

The pitch of the musical sounds produced by vibration of the strings can be determined by adjusting the free vibrating lengths of the strings. This can be accomplished in a number of ways: for example, as by the aid of mechanism illustrated in a patent issued on April 20, 1943, to John W. McBride, and having number 2,316,799. This mechanism includes a rotatable rod having an axis substantially parallel to the string and carrying a helical-like crest. The angular position of the rod determines which point of the crest contacts the string and, thereby, the free vibrating length.

It is one of the objects of this invention to improve in general the control mechanism for such rotatable rod mechanisms for determining the free lengths of vibration.

The strings in such instruments are usually stretched between two fixed points or bridges. Accordingly, "stopping" of the string at any intermediate point defines two lengths, respectively between the point of contact and the bridges. It is another object of this invention to co-ordinate these two lengths thus determined, so that either of them, or both, may be used, as desired. In order to facilitate such operation, the strings are longer than those that have been usually provided.

It is therefore still another object of this invention to provide an instrument having relatively long strings, each capable of operation to provide a pair of usable free vibrating lengths.

It is still another object of this invention to provide a readily manipulable string damping device that can be used to stop string vibrations.

This invention possesses many other advantages, and has other objects which may be made more easily apparent from a consideration of one embodiment of the invention. For this purpose there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawings:

Figure 1 is a top plan view of an instrument incorporating the invention;

Fig. 2 is a side elevation, partly in section, taken along plane 2—2 of Fig. 1;

2

Fig. 3 is an enlarged fragmentary plan view, partly in section, of that portion of the instrument which provides the control of the free vibrating lengths of the strings;

5 Fig. 4 is a sectional view, taken along plane 4—4 of Fig. 3;

Fig. 5 is a sectional view, taken along plane 5—5 of Fig. 3;

Fig. 6 is a sectional view, taken along plane 10 6—6 of Fig. 4;

Fig. 7 is a fragmentary sectional view, taken along plane 7—7 of Fig. 1, a part of the section being broken away to reduce the size of the figure;

15 Fig. 8 is an enlarged sectional view, taken along plane 8—8 of Fig. 2;

Fig. 9 is a fragmentary bottom plan view, taken in the direction of the arrow 9 of Fig. 2;

Fig. 10 is a sectional view, taken along plane 20 10—10 of Fig. 3;

Fig. 11 is a fragmentary sectional view, taken along plane 11—11 of Fig. 10;

Fig. 12 is an enlarged sectional view, taken along plane 12—12 of Fig. 6; and

25 Fig. 13 is a wiring diagram, illustrating the manner in which the electric pick-ups for the vibrating strings may be controlled for tone and volume.

The operating parts of the instrument are 30 supported upon a body 1, that may be fashioned of wood, or similar material. The body 1 is shown as provided with appropriate cavities for the accommodation of parts of the instrument, as will appear hereinafter.

35 String structures 2, 3, 4, and 5 (Figs. 1, 3, 5, and 8) are disposed in substantially parallel relation over the top of the body 1. Although single strings are shown for each of the string structures, it is, of course, possible to utilize multiple strings for any of them.

40 Provisions are made for tensioning each of the strings along the length of the body. At the right hand end of the body 1 (Figs. 1 and 2) there is shown a bridge 6.

45 This bridge is provided with grooves 7 in which are disposed the string structures 2, 3, 4, and 5. The bridge 6 may be appropriately fastened into a transverse groove formed in the body 1. The strings then extend toward the right and downwardly through apertures formed in the body 1, into the enlarged cross slot 8. Knots 9, or other enlargements, carried by the ends of the strings, serve to anchor the right hand ends of the strings in the slot 8.

50 At the left hand end of the instrument of the body 1, a bridge 10 is provided, constructed and 55

supported similarly to bridge 6. All of the strings 2, 3, 4, and 5 extend over the bridge 10. Accordingly, the bridges 6 and 10 form spaced points between which the strings may be tensioned.

For applying tension to the strings, pins 11 are provided upon which the strings are wound. Pins 11 are arranged to be rotated in any conventional manner for adjusting the tension of the strings, as by the aid of the pegs 12.

Provisions are made for stopping each of the strings 2, 3, 4, and 5 along the length of any string. For this purpose, use is made of a plurality of rotatable rods 13, 14, 15, and 16, disposed in a longitudinal cavity 23. These rods are similar to those illustrated and described in the prior patent hereinbefore referred to. They each carry a helical-like crest 17, 18, 19, or 20 (Figs. 3 and 5). In the present instance, all of the rods are shown as hollow; in this way, excessive weight is avoided when metal is used for the rods. These rods, furthermore, may be rotatably supported at their right hand ends by the aid of integrally formed stub shafts 21 (Fig. 2). These stub shafts are accommodated within bearing apertures in the bracket 22, carried by the upper surface of the body 1.

The left hand ends of the rods 13, 14, 15, and 16 are rotatably supported by the aid of structure most clearly illustrated in Figs. 3 and 4. Thus, each of the hollow rods is provided with a hollow tubular extension 24, 25, 26, or 27. Within these tubular extensions project the hollow tubular shafts, such as 28, upon which the extension 25 is journalled. Shaft 28 is supported in a wall 29, shown as extending upwardly from a plate 30. The plate 30 is disposed in the recess 23 of the body 1 and underneath the extensions 24, 25, 26, and 27. Each of the hollow shafts may be provided with the heads 31, 32, 33, and 34, which abut the left hand side of the wall 29. They are held fixed in position by the aid of the set screws 35. Thrust collars, such as 60, may, if desired, be provided between the left hand ends of each of the extensions 24, 25, 26, and 27, and the wall 29.

The heads 31, 32, 33, and 34 are provided for facilitating angular adjustment of the shafts associated with them, for a purpose that will be described hereinafter. For facilitating such angular adjustment, each of the heads may be provided with a series of angularly spaced slots 36 for the accommodation of a screw driver blade, or the like. The end of the blade may be conveniently inserted in an available slot 36 for exerting a thrust to produce a rotary torque on the head.

The wall 29 is arranged at an intermediate portion of the strings 2, 3, 4, and 5; accordingly, the crests 17, 18, 19, and 20 of the rotatable rods 13, 14, 15, and 16 extend from about the central portion of each string toward the right hand ends thereof. By angular adjustment of these rods, the helical-like crests are caused to stop the string at any point along the lengths of the crest. In this way, there are two effective vibrating lengths for each string: one defined between the left hand bridge 10 and the point of contact of the crest; and the other defined between the right hand bridge 6 and the point of contact of the crest. The strings 2, 3, 4, and 5 are purposely made long enough so that these two sections of the strings may be vibrated by the player, either in unison or separately, as he may choose.

In this manner it is possible to obtain variations of string length from a minimum as little as desired to a maximum which corresponds, substantially, to the entire length of a string be-

tween the bridges 6 and 10. The limits of string length occur when the helical-like crest contacts the corresponding string at the extreme right hand part of the crest. The minimum length then corresponds to the distance between the bridge 6 and the right hand end of the crest. Correspondingly, the maximum length of the string also occurs at this time, and corresponds to the distance between the bridge 10 and this point of contact.

The mechanism for rotating the rods 13, 14, 15, and 16 is shown to best advantage in Figs. 3, 4, and 5. This mechanism is quite similar to that described in the said prior patent. It includes the use of racks and pinions for the rotation of the rods.

Since this mechanism is similar for each of the rods, but one of them will be described in detail: that which is associated with the rod 14. The hollow extension 25 of this rod carries a pinion 37. This pinion is in mesh with a rack 38. Rack 38 is mounted upon the top surface of a manually operable key member 39. This key member is slidable transversely of the axis 20 of rotation of the pinion 37. To provide a guide for the key 39, side walls 40 and 41 are shown as extending upwardly from the bottom plate 30 (see also Figs. 10 and 11). Each of these walls is provided with a series of deep slots, such as 42 and 43, adjacent the bottom of the walls, to permit the passage of the racks 38. Furthermore, from the sides of these slots extend transverse narrow slots in which the edges of the respective keys are slidably mounted. In this manner, relatively widely spaced guides are provided; and there is a corresponding assurance against any of the keys binding in the guides.

For facilitating manipulation of the keys, they are each provided with an upper extension 44 joined to the key 39, as by the aid of the intermediate portion 45 (Fig. 5). These portions 45 of each of the key members provide places where finger pressure may be applied to urge the racks 38 inwardly, or toward the right, as viewed in Fig. 5.

Limits are provided for the movement of the keys 39. For this purpose, each of the keys is provided with a pair of spaced stops 46 and 47 (Figs. 5 and 10). Co-operating with all of the stops on all of the keys is a transverse stop bar 48. This bar is accommodated in a support 49. This support 49 is shown as extending along the right hand edge of the plate 30. This support 49 has a slot for the accommodation of the stop 48, as shown most clearly in Fig. 5. In order to hold the stop 48 against withdrawal upwardly from the slot, the slot is provided with a series of covering portions 50 (Figs. 10 and 11). The spaces between these portions 50 correspond to the spacing of the racks 38.

When the keys 39 are released, spring pressure is utilized to urge the keys to the extreme left hand position, as illustrated in Fig. 5. For this purpose, a torsion spring is placed inside each of the hollow extensions 24, 25, 26, and 27. The torsion spring 51, associated with the hollow extension 25, is shown in Figs. 3 and 4. The description of the manner in which this spring is accommodated and supported serves as a description for the spring supports in all of the extensions 24, 25, 26, and 27.

The right hand end of the spring 51 is telescoped over the cylindrical member 52 and is permanently anchored thereto. This cylindrical member 52 is formed integrally with a block 53

fastened within the rod 14, as by the screw 54. The left hand end of the spring 51 is similarly anchored to a cylindrical member 55 that is formed integrally with a block 56 disposed in the extension 25. This block 56 has a cylindrical member 57 extending into the hollow bearing member 28. A pin 58 extends radially from the member 57 and is accommodated in a sloping slot 59 of the bearing member 28. The torsion of the spring is in such direction that the pin 58 is urged into the bottom of the slot 59.

Furthermore, the torsion provides a force constantly urging the corresponding bar 13, 14, 15, or 16 to rotate in a clockwise direction, as viewed in Fig. 5; that is, in a direction to move the keys 39 outwardly. Adjustment of the torsional force of the spring is readily accomplished by angular adjustment of the bearing member 28. This angular adjustment is facilitated by the aid of a screw driver blade, or the like, co-operating with the slots 36 formed in the head 32 of the bearing member, all as explained hereinbefore. During adjustment the set screws 35 are, of course, released.

From the foregoing it is seen that the bearing member 28 serves two functions: one, to support the rod 14 so that it may rotate, and another, to provide a convenient adjustment of the spring torsion.

In order to facilitate adjustment of the angular position of each of the rods 13, 14, 15, and 16, fret marks may be provided. Such fret marks are shown most clearly in Fig. 3. They constitute a set of marks 61 disposed on one side of the crest, and a corresponding set of marks 62 on the other side of the crest. Each set is intended to be used respectively with the two sections of the string being stopped; set 61 indicates the tone produced by the string section between the crest and bridge 6; and set 62 indicates the tone produced by the string section extending between the crest and bridge 10.

Provisions are made for covering the key mechanisms, and in such manner that the cover may be lifted when desired. Accordingly, a sheet metal cover 63 (Figs. 1, 2, 4, 5, and 10) is shown as extending over the left hand ends of the rotatable rods 13, 14, 15, and 16. This cover is provided with a pair of bearing ears 64 (see particularly Fig. 3). One of the ears 64, as shown most clearly in Fig. 3, co-operates with a bearing pin 65 formed on the end of a bearing screw 66. This bearing screw 66 is supported adjacent the top of a bar 67 that is fastened to the top of the walls 40 and 41. The other ear 64 similarly cooperates with a bearing pin supported adjacent the top of the wall 29.

The vibrations of the string structures 2, 3, 4, and 5 are caused to affect an electric pick-up circuit. The pick-up devices are indicated in Figs. 1 and 2. They may comprise magnetic projections 68 and 69, respectively adjacent the bridge 6 and the bridge 10 underneath the string structures, which are purposely made from magnetic material. These magnetic projections co-operate with the strings, and form elements of an electric pick-up device, such as 70 or 71, disposed in appropriate cavities in the body 1. These two sets of pick-up devices 68 and 69 co-operate respectively with the sections of the strings defined by the points of contact of the crests on rod 13, 14, 15, or 16.

The two pick-up devices 70 and 71 may be connected in parallel to a common output circuit, as indicated in Fig. 13. Thus, the pick-up device

70 is shown as connected by the aid of leads 72 and 73 to the output leads 74 and 75. The pick-up device 71 is similarly connected, as by a lead 76, to the output lead 74. The other output lead 75 is connected to the opposite terminal of pick-up device 71 through a conducting bar 77 and an adjustable resistance 78. This adjustable resistance 78 is shown as disposed in a cavity 79 (Fig. 2) in the body 1. Resistance 78 may be controlled by the aid of a rotary adjusting member 80 that lies substantially flush with the upper surface of body 1. This resistance 78 is adjusted in such manner as to ensure that there is no undesired circulation of energy between the two pick-up devices, and so that they may properly function in parallel.

In order that the instrument be capable of performing most effectively, it is desirable that both the tone and volume of the produced sound be under control of the player. This can be done electrically in many ways; but, in the present instance, the control of tone and volume is greatly simplified.

The stationary parts of the control device are shown as supported upon an insulation panel 81 (Figs. 6 and 12). This insulation panel is appropriately attached, as by screws 82, to the bottom of a cavity 83 formed in the body 1.

The tone and volume control includes elements of high impedance that are variable and that may be connected in parallel to the pick-up device 70 and 71. In the present instance these impedance devices are in the form of molded or ceramic resistances fastened to the top of the panel 81 and indicated by reference characters 87 and 88. The exposed upper surfaces of these resistances are intended to be contacted by sliding spring fingers 89 and 90. The structure and the supports for these fingers will be described hereinafter.

Resistance 87 is associated with the tone control, and resistance 88 is associated with the volume control. As indicated most clearly in the diagram, Fig. 13, these molded resistances are so constructed that equal increments of movement along the length of the resistance correspond to unequal resistances. Thus, in both cases, for equal increments of movement of the contacts 89 and 90 from the extreme limiting left hand end of each of the resistances and toward the right hand end, the increments of resistance decrease to the central taps 84 and 92; and from then on the increments of resistance increase for equal increments of movement of the contacts.

The contacts 89, 90, are formed respectively integrally with contacts 86 and 85 (Fig. 6) that bear upon the bus bars 84 and 77 respectively. Thus, these contacts form the ends of the legs of a pair of U-shaped structures 93 and 100, made from resilient metal.

The volume and tone controls can be described effectively in connection with Fig. 13. When the contacts 85, 86, 89, and 90 are at the extreme left hand position with respect to the bars 77 and 84 and the resistances 87 and 88, then the contact finger 89 is in contact with the extreme left hand portion of the tone control resistance 87. The contact point 90 is out of contact with the volume control resistance 88, since this resistance does not extend so far toward the left as resistance 87. In this position, a high resistance is in series with a tone control filter 94, which is placed in parallel across the output leads 74 and 75. This parallel circuit may be traced as follows: From lead 74, connection 93, bar 84, contacts 86 and 89,

resistance 87, central tap 91, through filter 94, and connection 95 to the lead 75.

Movement of the contact structure 99-100 toward the right gradually reduces the resistance in this tone control circuit. This resistance reaches a minimum when the contact point 89 is at center tap 91. From that stage on, further movement of contact 89 toward the right causes resistance to be inserted in the tone control circuit at an increasing rate. This resistance becomes infinite as the contact 89 is moved beyond the right hand end of resistance 87.

The volume control is effected by aid of resistance 88 that is simply connected in parallel to the pick-ups 70 and 71. In the first movement of the contacts 85, 86, 89, and 90 from the extreme left hand position to a position corresponding to the center tap 91 of the tone control, the volume control resistance 88 is disconnected. However, in the movement of the contacts from a position corresponding to the center tap 91 to a position corresponding to the center tap 92 of resistance 88, both the tone control resistance 87 and the volume control resistance 88 are in active engagement with their respective contacts 89 and 90. The parallel circuit of the volume control may be traced as follows: from lead 74, connection 96, center tap 92, contact point 90, connection 97, contact 85, bar 77, to the output lead 75.

As the contact 90 moves from left to right, as viewed in Fig. 13, increments of resistance in the volume control are cut out of the circuit. These increments, for uniform movement of the contacts, decrease as the center tap 92 is approached. When contact 90 is in a position corresponding to this center tap, the resistance is at a minimum and the volume is greatly reduced. Continued movement of the contacts toward the right causes an increase in the resistance in the volume control by ever increasing increments, corresponding to a gradual increase in volume.

During that interval of movement between center taps 91 and 92, the tone and volume controls are simultaneously active. Movement of the contacts 85, 86, 89, and 90 between the left hand limit of motion and the center tap 91 corresponds to control of tone alone; and, similarly, movement of the contacts to the right away from center tap 92 corresponds to control of volume alone.

Continuous movement in one direction of the contacts 85, 86, 89, and 90 thus produces three phases of operation: one, in which only one of the control impedances is varied; two, when both impedances are varied; and three, when the other of the two impedances alone is varied.

Contacts 85, 86, 89, and 90 may be conveniently supported by the aid of the arm 98 (Figs. 4, 6, and 12). This arm 98 carries the U-shaped members 99 and 100, the arms of which terminate in the contacts 85-90 and 86-89 respectively. These conductors 99 and 100 are insulated from the arm 98, as indicated diagrammatically in Fig. 12. This may be accomplished by the provision of insulation layers 101, 102, and bushings 103.

The arm 98 forms one arm of a lever 105 which is rotatable on an axis 104 (Figs. 4, 5, and 6). For this purpose the lever 105 is provided with a downwardly extending cylindrical projection 106 that is journaled in a bearing sleeve 107 supported in the bottom of the body cavity 108. This bearing sleeve 107 is shown as provided with a relatively wide flange 109, by the aid of which it may be secured to the body 1. The lower end

of the projection 106 is provided with a squared end for the accommodation of the manually operable lever 110 that is located at the bottom of the body 1. This lever is provided with a finger receiving portion, or saddle, 111 (Figs. 2, 4, and 9) by the aid of which a player can manipulate the lever 105 from the lower side of the body 1.

Angular movement of lever 105 can also be accomplished from above the body 1 by the aid of the upwardly extending projection 112 fastened to the lever 105 (Figs. 2, 4, and 5). This projection 112 likewise terminates in a finger receiving portion 113 capable of being manipulated, as by the thumb of the player. The portion 112, as shown most clearly in Figs. 3 and 6, is permitted freedom of motion by the aid of a recess defined by the arcuate wall 114 in the body 1. The body 1 may also be provided with a longitudinal recess, such as recess 115 (Figs. 5 and 6) for the accommodation of the leads 116 extending to the pick-up device 71.

In playing the instrument, it may be desirable at times to damp the vibrations in those sections of the string structures that are not to be vibrated. For this purpose felt damper pads 117 and 118 are provided. These damper pads are shown to best advantage in Figs. 1, 2, 3, 4, and 7. They are arranged transversely of the strings, and extend through appropriate slots in the metal plates 119 and 120 respectively.

Damper pad 118 is shown as fastened into a U-shaped trough-like member 121 (Fig. 7). This support, in turn, is carried by the arms 122 and 123 (see also Fig. 8). These arms, in turn, are shown as attached to a bar 124 that is pivotally mounted in the ears 125 projecting below the plate 120. Rocking of the bar 124 is accomplished by the aid of the arms 126 and 127, depending from the bar 124. The linkage whereby these arms 126 and 127 are operated will be described hereinafter.

Damper pad 117 is similarly supported by the aid of the plate 119. It, too, is provided with an operating arm 129.

To move arms 126 and 127 in unison, their lower extremes are joined by link 130 (Figs. 3, 5, 6, 7, and 8). This link extends through an appropriate recess 131 extending longitudinally of the body 1.

The manner in which the link 130 is connected to the arms 126 and 127 is shown most clearly in Figs. 6, 7, and 8. Arm 126 has a hub 132. Since the structures for both dampers are similar, only that associated with the left hand hub 132 need be described. A bar 133 is threaded into hub 132. This bar 133 is pivotally supported in the clevis 134 joined to the link 130, the ears of which are disposed on the opposite sides of the hub 132. Similarly, the lower end 60 of arm 127 is provided with an aperture for the passage of the bar 133.

The left hand end of bar 133 is spaced from the arm 127, as by a spacer sleeve 135. This sleeve is disposed between the arm 127 and an arm 136 that extends through a slot 137 in the bottom of the body 1. The bar 133 is provided with a slotted head 138 to facilitate assembly. The arm 136, as will be explained hereinafter, is provided for manipulation of the dampers 117, 118 from below the body 1.

Manual movement of link 130 is accomplished by the hand or finger of the player, accommodated in a saddle-like structure 139 (Figs. 1, 2, and 7). This structure 139 is shown as extending above the body 1, and carried by the support

140, shown as integrally formed with the link 130. Furthermore, movement toward the right, as viewed in Fig. 7, will cause damper 118 to be active and damper 117 to be released. Movement toward the left causes damper 117 to be active and damper 118 to be released. In the intermediate position illustrated, neither damper is active.

Provisions are made for operating the dampers from below the body 1. It is for this purpose that arm 136 (Figs. 4, 5, 8, and 9) is utilized. In addition, another arm 141, spaced from arm 136, is also joined to the bar 133. It extends downwardly through a slot 142. The lower ends of these bars 136 and 141 are rigidly fastened to an operating plate 143 of general triangular configuration. This operating plate 143 is disposed at the bottom side of the instrument for ready manual operation by the player. For facilitating such operation, a projection 149 (Fig. 2) is formed on the plate 143. By movement of plate 143 toward the left of the body 1, the arms 136 and 141 are caused to operate the arms 126 and 127, and thereby the damping devices are likewise operated. Since the arms 136 and 141 are moved angularly about the axis of bar 133, the plate 143 is permitted to tilt during movement of the plate.

For this purpose, the plate 143 is supported at its right hand end by the aid of an elongated socket 144 carried integrally of the plate at its right hand portion. This socket provides a passageway 145 into which is accommodated the ball end 146 of a stationary arm 147 (Fig. 4), and is attached to the bottom of the body 1, as by the aid of the plate 148. The ball 146 permits limited universal movement of plate 143. The plate is retained in proper position at its forward, or left hand, end, since it is permanently attached to the lower ends of arms 136 and 141.

The damper operating arms 122 and 123 can be urged by the player strongly enough to lift the strings from the crests on the rods 14, 15, 16, and 17. In this way, it is possible to rotate any of the crested rods while the strings are out of contact with the rods. Accordingly, it is possible to adjust the free vibrating lengths abruptly.

The inventor claims:

1. In a musical instrument, a string, means for tensioning said string between two fixed points, mechanism for stopping the string along points extending between an intermediate portion of the string and one of the fixed points, and means for rendering the vibrations of both portions of the string, as defined by the stopping means, optionally effective to produce sound.

2. In a musical instrument, a string, means for tensioning said string between two fixed points, a rotatable rod beneath the string and provided with means to stop the string along any of a series of points that extend between an intermediate portion of the string and one of the fixed points, and in accordance with the angular adjustment of the rod, and means for rendering the vibrations of both portions of the string defined by the stopping means, to be optionally effective to produce sound.

3. In a musical instrument, a tensioned string, a rotatable rod having an axis substantially parallel with the string, said rod having provisions for determining the free length of vibration of the string, and in accordance with the angular position of the rod, said rod having a hollow extension, a torsion spring in said ex-

5 tension for urging the rod to rotate in one direction, means for attaching one end of the spring in the extension, means for anchoring the other end of the spring, and means for moving the rod angularly against the torsion of said spring, including a member mounted exteriorly on said hollow extension.

4. In a musical instrument, a tensioned string, a rotatable rod having an axis substantially parallel with the string, said rod having provisions for determining the free length of vibration of the string, and in accordance with the angular position of the rod, said rod having a hollow extension, a torsion spring in said extension for urging the rod to rotate in one direction, means for attaching one end of the spring in the extension, means forming a bearing for the rod and co-operating with the interior surface of the extension, means joining the other end of the spring with the bearing forming means, and means for adjusting the force of said spring by angular adjustment of said bearing forming means.

5. In a musical instrument, a tensioned string, means for determining the free vibrating length 20 of the string, a vibration damper arranged laterally of the string, and means for moving said damper to active or inactive position.

6. In a musical instrument, a string, means for tensioning said string between two fixed points, string contacting means operating intermediate said points to provide a pair of free vibrating string sections, a pair of vibration damper means arranged respectively laterally of the string sections, and a common means for operating said dampers.

7. In a musical instrument, a string, means for tensioning said string between two fixed points, string contacting means operating intermediate said points to provide a pair of free vibrating string sections, a pair of vibration damper means arranged respectively laterally of the string sections, and a common means for operating said dampers in such manner that, as one moves away from the associated section, the other damper approaches its corresponding section.

8. In a musical instrument, a body, one or more strings supported on the body, means for tensioning said strings between two fixed points, means for adjusting the free vibrating lengths of the strings, a vibration damper arranged laterally of the strings, and means for operating said damper from either the top or bottom of the body.

9. In a musical instrument, one or more strings, means for tensioning said strings between two fixed points, a rotatable rod associated with each string and having an axis substantially parallel to the string, as well as a helical-like crest for forming two vibrating string sections, defined by said fixed points and the crest, and means for angularly adjusting the rods, each of said crests having a pair of sets of fret marks respectively on each side of the crest, the sets of marks being respectively related to the two fixed points for indicating the tones corresponding to the string sections.

10. In a stringed musical instrument, one or more tensioned strings, means including a movable crest adapted to contact the string, for adjusting the free length of the string by small increments, a damper extending across the string, and means for so operating the damper as to lift the string off the crest.

JOHN W. McBRIDE.
